US0D1112426S

(12) **United States Design Patent** (10) **Patent No.:** **US D1,112,426 S**
(45) **Date of Patent:** **** Feb. 10, 2026**

(54) **ELECTRONIC DEVICE**

(71) Applicant: **HUDDLY AS**, Oslo (NO)

(72) Inventors: **André Lyngra**, Skjetten (NO); **Knut Helge Teppan**, Asker (NO); **Niklas Schmidt**, Oslo (NO); **Mona Kleven Lauritzen**, Oslo (NO); **Xiyu Hu**, Oslo (NO); **Sean Collins**, Kurland (NO)

(73) Assignee: **HUDDLY AS**, Oslo (NO)

(**) Term: **15 Years**

(21) Appl. No.: **29/948,215**

(22) Filed: **Jun. 20, 2024**

(51) **LOC (15) Cl.** **16-01**

(52) **U.S. Cl.**

USPC **D16/202; D14/125**

(58) **Field of Classification Search**

CLAIM

The ornamental design for an electronic device, as shown and described.

DESCRIPTION

FIG. 1 is a front, right perspective view of the electronic device, showing the new design;

FIG. 2 is a front elevation view thereof;

FIG. 3 is a rear elevation view thereof;

FIG. 4 is a left side elevational view thereof;

FIG. 5 is a right side elevational view thereof;

FIG. 6 is a top plan view thereof; and,

FIG. 7 is a bottom plan view thereof.

The broken dashed lines of even length illustrate portions of the electronic device that form no part of the claimed design.

1 Claim, 7 Drawing Sheets
